His Attorney.

UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

1,366,667.

Specification of Letters Patent. Patented Jan. 25, 1921.

Application filed November 18, 1919. Serial No. 338,997.

To all whom it may concern:

Be it known that I, OSCAR JUNGGREN, a citizen of the United States, residing at Schenectady, in the county of Schenectady, 5 State of New York, have invented certain new and useful Improvements in Elastic-Fluid Turbines, of which the following is a specification.

The present invention relates to elastic 10 fluid turbines particularly to the bucket wheels and has for its object to provide an improved structure and arrangement for fastening the buckets to the rim of a wheel.

For a consideration of what I believe to be 15 novel and my invention, attention is directed to the accompanying description and the claims appended thereto.

In the drawing, Figure 1 is a side elevation of a portion of a bucket wheel embodying my invention and Fig. 2 is a radial sectional view thereof.

Referring to the drawing, 3 indicates the web of the wheel or rotor and 4 the rim thereof upon which the ring of buckets 5 is 25 mounted. On opposite sides rim 4 is provided with annular shoulders 6 and annular grooves 7 thereby providing an annular head 8 having undercut sides. The bucket bases are provided with slots forming two 30 legs or furcations 9 which straddle head 8. On their inner ends legs 9 are provided with inwardly facing projections 10 which fit into grooves 7 and engage under head 8. Shoulders 6 are provided with annular 35 projections 11 behind which projections 12 on the extremities of legs 9 are located to prevent the legs from spreading. The buckets will be assembled on the rim in the usual manner, one or more filling slots, (not 40 shown) being provided in the rim as is well understood. 14 indicates the bucket cover.

The bucket fastening means as just described forms what is termed the inverted dovetailed type of fastening and in itself is 45 well known. It may be taken as typical of a suitable type of fastening means in connection with which my invention may be carried out.

Now, according to my invention, I fasten 50 the turbine buckets to the wheel in groups, the buckets of each group being fastened to each other by fastening their bases together in a suitable manner such as by welding, and their outer ends together by means of the 55 bucket cover. Each group may comprise a

suitable number of buckets, for example, from 6 to 8 or more, and the bucket cover will be made in sections of such length that each section just spans one group. In Fig. 1 of the drawing, one group and a part of 60 the group on each side thereof is shown. Such group extends from *a* to *b* and is shown as comprising seven buckets. The bases are illustrated as being fastened together by providing them with grooves 15 65 on opposite sides which grooves, after the buckets have been assembled on the wheel, are filled with metal 16 as by the arc welding process so all the bucket bases of the group are rigidly united. The bucket bases 70 of a group may however, be united in other ways, such as by copper brazing, for example, and if found desirable, the bucket groups may be formed prior to mounting the buckets on the wheel.

The bucket cover, in addition to being fastened by tenons 17, as indicated, is also preferably welded or brazed to the bucket ends so the bucket cover will be firmly supported at all points.

With the above described arrangement wherein the buckets are attached to the wheel in groups the buckets of each group being firmly united, it will be seen that there is no possibility for any bucket to move 85 individually or yield at its base in such manner as to permit it to incline slightly, which may result in breaking of the bucket cover or of the tenons. Furthermore, if any individual bucket base does not fit the rim 90 well nevertheless it cannot loosen or move since it is held by adjacent buckets.

In accordance with the provisions of the patent statutes, I have described the principle of operation of my invention, together 95 with the apparatus which I now consider to represent the best embodiment thereof, but I desire to have it understood that the apparatus shown is only illustrative and that the invention may be carried out by other 100 means.

What I claim as new and desire to secure by Letters Patent of the United States, is:

1. In an elastic fluid turbine, a rotor having a rim provided with a groove, and buckets having bases provided with projections which engage in said groove to fasten the buckets individually to the rim, said bucket bases being fastened to each other by fusion of metal to form groups.

2. In an elastic fluid turbine, a rotor having a rim provided with a groove, buckets having bases provided with projections which engage in said groove to fasten the buckets individually to the rim, and a sectional bucket cover fastened on the ends of said buckets, said bucket bases being fastened to each other by fusion of metal to form groups.
10. 3. A turbine rotor comprising a rim provided with a groove, buckets having projections which fit into said groove to fasten the bucket to the rim, and a sectional bucket cover, characterized by the fact that the 15 bucket bases are united by fusion of metal to form bucket groups whereby any bucket is prevented from moving individually.
4. A turbine rotor having the buckets fastened thereon individually by dovetailed 20 connections characterized by the fact that the buckets are formed into groups by uniting the bases of successive series of buckets
- together by fusion of metal, and fastening their outer ends together with bucket cover sections. 25
5. In an elastic fluid turbine, a rotor having a rim with grooves therein, and buckets having projections which project into said grooves to fasten the buckets individually on the rim, said buckets being arranged in 30 groups, each group comprising a plurality of buckets fastened together at their bases and outer ends.
6. In an elastic fluid turbine, a rotor having a rim and buckets having bases, said 35 bases being fastened to the rim by dovetailed connections, said buckets being arranged in groups, each group comprising a plurality of buckets having their bases welded together and a bucket cover section 40 welded to their outer ends.

In witness whereof, I have hereunto set my hand this 17th day of November 1919.

OSCAR JUNGGREN.
